SUGAR BOWL

Earl S. Tupper, Upton, Mass.

Application October 5, 1946, Serial No. 133,773

Term of patent 14 years

(Cl. D44—15)

To all whom it may concern:

Be it known that I, Earl S. Tupper, a citizen of the United States, residing at Upton, in the county of Worcester, and State of Massachusetts, have invented a new, original, and ornamental Design for a Sugar Bowl, of which the following is a specification, reference being had to the accompanying drawing, forming part thereof.

Fig. 1 is a front view of a sugar bowl, showing my new design;

Fig. 2 is a side elevational view thereof;

Fig. 3 is a view in top plan, showing my new design.

I claim:

The ornamental design for a sugar bowl, as shown.

EARL S. TUPPER.
